(57) CLAIM

The ornamental design for an aerosol container, as shown and described.

DESCRIPTION

FIG. 1 is a perspective view of an aerosol container with its structural environment shown in dotted lines;
FIG. 2 is a front end elevational view thereof;
FIG. 3 is a rear end elevational view thereof;
FIG. 4 is a left side elevational view thereof;
FIG. 5 is a right side elevational view thereof; and,
FIG. 6 is a top view thereof.

The broken line showing of portions of the container are for illustrative purposes only and form no part of the claimed design.
